UNITED STATES PATENT OFFICE.

FRANK P. D'ARCY, OF KALAMAZOO, MICHIGAN.

CUSHION STRUCTURE.

1,172,344.

Specification of Letters Patent. Patented Feb. 22, 1916.

Application filed September 20, 1915. Serial No. 51,588.

To all whom it may concern:

Be it known that I, FRANK P. D'ARCY, a citizen of the United States, residing at Kalamazoo, Kalamazoo county, State of Michigan, have invented certain new and useful Improvements in Cushion Structures, of which the following is a specification.

This invention relates to improvements in cushion structures.

10 The main objects of my invention are: First, to provide an improved cushion structure in which the upholstering is secured without the necessity of stitching or sewing. Second, to provide an improved cushion structure in which the upholstering cover is provided with a metal binding edge so that it is protected from wear at the bottom of the cushion where the cushion rests upon a seat. Third, to provide an improved cushion structure having these features which is attractive in appearance and at the same time very economical to produce, the parts being easily and quickly assembled by unskilled labor.

25 Further objects, and objects relating to structural details, will definitely appear from the detailed description to follow.

I accomplish the objects of my invention by the devices and means described in the 30 following specification.

The invention is clearly defined and pointed out in the claims.

A structure which is a preferred embodiment of my invention is clearly illustrated 35 in the accompanying drawing, forming a part of this specification, in which:

Figure I is a detail inverted view of my improved spring cushion. Fig. II is a detail vertical section from front to rear of 40 my improved cushion. Fig. III is an enlarged detail section on a line corresponding to line 3—3 of Fig. I, showing details of the securing means. Fig. IV is an enlarged detail section on a line corresponding to line 4—4 45 of Fig. I, showing the arrangement of the covering, which provides a buffer for the cushion. Fig. V is a detail perspective view of one of the cover retaining or binding members before it is applied to the cushion. 50 Fig. VI is a detail vertical section corresponding to that of Fig. II of a modified form of my invention.

In the drawing similar reference characters refer to similar parts throughout the 55 several views and the sectional views are

taken looking in the direction of the little arrows at the ends of the section lines.

Referring to the drawing, the cushion springs 1 are mounted on the sheet metal cross bars or supports 2, the details of the 60 mounting not being illustrated. The ends of the cross bars are rigidly secured to the bottom border frame 3 by folding the ends 4 of the cross bars around the border frame. The upper ends of the outer springs are connected to the top border frame 5 by means 65 of the coils or clips 6. The tops of the springs are also connected to each other and to the frame by means of the cross wires 7 and 8, thus supporting the springs in an up- 70 right position and providing a net-work for supporting the upholstery.

The backing 9 of the upholstering is drawn over the springs with its skirt or side 75 portions 10 embracing the sides thereof and wrapped around the bottom border wire at 11. The outer cover 12 is arranged over the filling 13 and the edges of its side or skirt portion 14 wrapped over the backing around 80 the border wire, as at 15.

The filling 13 is preferably arranged between the backing and the cover at the front end of the cushion, see Fig. II. The covering and backing are secured to the bottom frame wire and a binding is provided for 85 the cover by means of the binding or securing members 16. These binding or securing members 16 are formed of sheet metal and are first bent into a U-shape, as shown in Fig. V, and arranged over the border wire 90 with the backing and covering wrapped thereon and clamped upon the same into the cylindrical shape shown in Fig. III, the distance between the edges of the binding members being less than the diameter of the border wires with the cover wrapped thereon so that it is quite impossible to pull out 95 the edges of the cover. The parts are effectively secured together and also a metal binding is provided for the cover. 100

The corners of the frame border members are preferably curved as shown in Fig. I, the corner binding members being curved to correspond. The edges of the backing and covering are preferably lapped under 105 the ends of the cross or spring supporting bars to provide buffers 17, which serve to prevent rattling of the cushion in the event that it should be loose in its seat.

It is quite common practice, particularly 110

in automobiles, for which purpose my spring 5 cushions are desirable, to provide upstanding metal strips along the front edges of the seats for retaining the cushions. The binding and cover securing strips protect the edges of the covers so that they are not worn in use or abraded by contact with the seat. The retaining members can be suitably finished to prevent oxidation and they make 10 a very attractive finish for the cushion, obviating the necessity for sewing or the providing of finishing strips, and at the same time secure the covering even more effectively than by sewing. A further advantage 15 is that the work can be quickly done by unskilled workmen, the binding members being rapidly applied by means of pliers.

In the modification shown in Fig. VI the backing 18 and cover 19 are secured to a skirt 20 portion 20 by the seam 21. The skirt portion is secured to the border frame the same as in the structure shown in the other figures.

I have illustrated and described my improvements in two forms in which I have 25 embodied the same. I have not attempted to illustrate or describe various modifications and adaptations which are possible and might be desirable for the manufacture of cushions for different purposes, as I believe 30 the disclosure made will enable those skilled in the art to embody or adapt the same as circumstances may render desirable.

Having thus described my invention, what I claim as new and desire to secure by Letters Patent, is:

1. In a spring structure, the combination of the bottom border frame of wire, said frame being curved at the corners, coiled springs, spring supporting bars secured to 40 said border wire, a cushion cover having its lower edges wrapped around said border frame, and binding members of sheet metal curved in cross section disposed to embrace

said bottom border frame and said cover, the securing members at the corners being curved 45 to correspond with the curves of the corners of the border frame, the distance between the edges of said securing members being less than the diameter of the border frame whereby the cover is secured to the frame 50 and a metal binding edge provided for the cover.

2. In a spring structure, the combination of the bottom border frame of wire, coiled springs, spring supporting bars secured to 55 said border wire, a cushion cover having its lower edges wrapped around said border frame, and binding members of sheet metal curved in cross section disposed between said supporting bars to embrace said bottom border frame and said cover, the distance between the edges of said securing members being less than the diameter of the frame and a metal binding edge provided for the cover, 60 the cover being lapped below the ends of said cross bars to provide buffers.

3. In a spring structure, the combination of the bottom border frame of wire, coiled springs, spring supporting bars secured to 70 said border wire, a cushion cover having its lower edges wrapped around said border frame, and binding members of sheet metal curved in cross section disposed to embrace said bottom border frame and said cover, the distance between the edges of said securing 75 members being less than the diameter of the border frame whereby the cover is secured to the frame and a metal binding edge provided for the cover.

In witness whereof, I have hereunto set 80 my hand and seal in the presence of two witnesses.

FRANK P. D'ARCY. [L.S.]
